UNITED STATES PATENT OFFICE.

ARCHIE E. PARNALL, OF CHICAGO, ILLINOIS, ASSIGNOR TO FRANK W. WILLIAMS,
OF CHICAGO, ILLINOIS.

BRAKE FOR PHONOGRAHS.

1,345,397.

Specification of Letters Patent.

Patented July 6, 1920.

Application filed August 21, 1917. Serial No. 187,391.

To all whom it may concern:

Be it known that I, ARCHIE E. PARNALL, a citizen of the United States, and a resident of the city of Chicago, in the county of Cook and State of Illinois, have invented certain new and useful Improvements in Brakes for Phonographs; and I do hereby declare that the following is a full, clear, and exact description of the same, reference being had to the accompanying drawings, and to the numerals of reference marked thereon, which form a part of this specification.

This invention relates to an improved form of a brake mechanism for phonographs adapted to be manually operated to frictionally contact the governor and the record carrying disk simultaneously for the purpose of bringing the operating parts of the phonograph to rest in a very short time.

It is an object of this invention to construct a manually operated brake mechanism, adapted to frictionally engage the record carrying disk of a phonograph to bring said disk to a standstill after the playing of a record.

It is also an object of this invention to provide a brake mechanism adapted to simultaneously contact the governor and record plate of a phonograph to bring the same to rest after the playing of a record.

It is a further object of this invention to provide a phonograph brake mechanism embracing a plurality of brakes adapted to be manually actuated to simultaneously contact the phonograph governor and record disk to bring the same to a sudden stop after the playing of a record.

It is furthermore an object of this invention to provide a plurality of brake members operatively connected to a constant speed control lever which may be shifted to simultaneously move said brake members into frictional engagement with a phonograph record carrying disk and with a governor disk to bring the operating mechanisms of a phonograph to a sudden stop.

It is an important object of this invention to provide a phonograph brake mechanism adapted to frictionally contact a plurality of operating parts of a phonograph to bring said parts to rest within a very short time after the playing of a record.

Other and further important objects of

this invention will be apparent from the disclosures in the drawings and specification. 55

The invention (in a preferred form) is illustrated in the drawings and hereinafter more fully described.

On the drawings:

Figure 1 is a top plan view of a phonograph with the record carrying disk partly broken away to show a brake mechanism embodying the principles of this invention.

Fig. 2 is a view taken on line 2-2 of Fig. 1, with the casing parts omitted to show the working mechanisms.

Fig. 3 is an enlarged detailed section taken on line 3-3 of Fig. 1, with parts omitted and broken away and with parts shown in elevation.

Fig. 4 is a bottom plan detail view of the record disk brake lever.

Fig. 5 is a section taken on line 5-5 of Fig. 1.

Fig. 6 is an enlarged detail section taken on line 6-6 of Fig. 1.

As shown on the drawings:

The reference numeral 1, indicates the top board of a phonograph case, having rotatably mounted thereabove in the usual manner, a record carrying disk or plate 2, secured upon the upper reduced and projecting end of a vertical driving shaft 3, which is disposed to project centrally through the top board 1. The driving mechanisms are mounted within a framework which is rigidly secured by screws or any other suitable means to the inner or under surface of the top board 1, and comprises an upper frame plate 4, and a lower frame plate 5, spaced from one another by means of braces or standards 6, which are formed on the upper frame plate 4, and are internally threaded to receive retaining screws 7, for holding the lower frame plate 5, in position. The driving shaft 3, is journaled in the frame plates 4 and 5, and has a portion thereof immediately above the reduced lower journaled end thereof formed to provide an integral pinion 8. The shaft pinion 8, meshes with a gear 9, rotatably mounted upon a stub shaft secured to the lower frame plate 5. Also mounted upon said stub shaft and rigidly secured to the upper surface of the gear 9, is a pinion 10, which is adapted to rotate with said gear 9, and meshes with a large gear base plate 11, which forms the

bottom of a motor casing 12, which is rigidly secured thereto and adapted to be rotated therewith. Secured upon the motor shaft above the casing 12, is a winding gear 13, adapted to mesh with a sprocket wheel (not shown) but secured on the inner end of a crank shaft 14, held in position by means of a bracket 15. Wound upon the crank shaft 14, is a locking spring 16, one end of which is secured to the frame plate 4, while the other end is free, thus affording an arrangement whereby the crank shaft 14, may be rotated in one direction only, a rotation in the opposite direction tending to force the spring to wind tightly on the crank shaft to lock the same against rotation in that direction. The outer end of the crank shaft is of course positioned to permit a handle (not shown) to be secured thereto for winding up the motor. It will of course be understood that an electric or any other suitable type of motor may be used if desired in place of the motor described.

Keyed or rigidly secured by other suitable means upon the vertical driving shaft 3, is a worm wheel or gear 17, which meshes with a worm formed on the inner end of a countershaft 18, journaled in suitable supporting brackets 19, formed or secured upon the under surface of the top frame plate 4. The speed of rotation of the countershaft 18, is controlled by a centrifugal governor mechanism of a familiar type, comprising weights 20, secured on spring arms 21, the inner end of each of which is secured to a drum wheel rigidly secured on the countershaft 18, to the outside of the worm thereof. The outer end of each of the spring arms 21, is secured to the hub of a slidable friction disk 22, which is adapted to be drawn inwardly, as the speed of the countershaft increases, due to the movement of the weights 20, outwardly away from the countershaft by centrifugal force. A friction brake is provided to bear against the inner surface of said friction disk 22, of the governor mechanism, and comprises a rubber contact head or brake shoe 23, secured upon the lower end of an arm 24, which extends upwardly through a suitable slot formed in the upper frame plate 4, and has the upper end thereof secured at right angles to one edge of a horizontal lever 25, one end of which is pivotally secured by a pivot 25^a, upon a boss formed upon the top frame plate 4. The other end of the lever 25, is bent upwardly at right angles to form a finger 26, which projects through an opening or aperture 27, formed in the top board 1, of the phonograph casing.

Disposed horizontally above the top board 1, and below the record carrying disk 2, is a speed regulating arm or starting lever 28, the inner end of which is apertured to engage over the upper projecting end of the

finger 26, and the outer end projects through a horizontal slot formed in an angle iron bracket plate 29, secured upon the top board 1, to the outside of the record carrying disk 2. Rigidly secured upon the top board 1, to one side of the aperture 27, is a small plate or link 30, to which the lever 28, is pivotally connected at a point 31, a short distance from its inner end. Formed integrally on one side of the lever 28, near the outer end thereof is an indicator or finger piece 32, adapted to contact the periphery of a cam shaped speed regulating dial plate 33, which may be manually rotated or adjusted by means of a knurled stem 34, for regulating the speed of rotation of the record carrying disk 2. Also pivotally connected to the lever 28, between the point 31, and the indicator 32, is an angled member or bell-crank comprising an arm 35, on the outer end of which is integrally formed at an angle thereto, a short arm 36, having a longitudinal slot 37, therein, into which projects a detent or projection 38, formed on the under surface at one end of a link or small plate 39, the other end of which is depressed and rigidly secured upon the top board 1, as shown in Fig. 1. Secured upon the angled member at the junction of the arms 35 and 36, is a friction drum or cylindrical brake shoe 40, covered with rubber and disposed to contact the periphery of the record carrying disk 2, when the starting lever 28, is in its normal position as shown in full lines in Fig. 1.

The operation is as follows: 100
When it is desired to use the phonograph, the motor is wound up by turning the crank shaft 14, by its handle, thereby rotating the sprocket wheel thereon, which in turn rotates the winding gear 13, and the motor shaft, thus winding the motor spring. In the normal position of the starting lever 28, as shown in Fig. 1, the brake shoe 23, contacts the friction disk 22, of the governor, and the brake shoe 40, is in contact with the periphery of the record carrying disk 2, thus holding the disk driving motor mechanisms stationary. To start the phonograph, the cam regulating dial 33, is first manually set by means of its stem handle 34, so that the indicator 32, is disposed opposite the mark on said dial for the desired rate of speed, and as shown in Fig. 1, said dial is set for the maximum speed of 105 revolutions per minute. The outer end of the starting lever 28, is now shifted in the slot of the angle iron 29, toward the dial 33, until the end of the indicator strikes against the periphery of the cam dial, as shown in dotted lines in Fig. 1. By the operation of 120 the starting lever 28, the arms 35 and 36, are moved or swung outwardly, thus moving the brake shoe 40, out of contact with the record carrying disk 2, and also simultaneously moving the inner apertured end of the 130

starting lever 28, inwardly, thus swinging the finger 26, and the lever 25, about its pivot and thereby also moving the brake shoe 23, and the arm 24, inwardly away from the governor friction disk 22. The stored energy of the motor, is thus permitted to exert itself and consequently rotates the motor casing 12, and the base plate gear 11, thereof, the winding gear 13, and the motor shaft, 10 being held stationary by the locking spring 16, on the crank shaft 14. With the rotation of the gear 11, the pinion 10, and the gear 9, are rotated, thereby rotating the vertical driving shaft 3, and the record carrying disk 2. The worm wheel 17, on the shaft 3, is also rotated, and being in mesh with the worm on the countershaft 18, rotates, the same and with it the governor mechanisms mounted thereon. The centrifugal force 15 exerted upon the governor weights, forces the same away from the countershaft, thereby drawing the governor friction disk 22, inwardly against the governor brake shoe 23, which is made of rubber or other suitable material to insure a smooth noiseless operation. 20 The brake shoe thus limits the inward movement of the disk 22, and consequently permits the record carrying disk 2, to rotate only at a constant speed, as indicated on the 25 cam dial 33.

To stop the operating mechanisms of the phonograph, the starting lever 28, after the playing of a record, may be moved into its normal position, thus simultaneously moving the brake shoe 40, into frictional engagement with the periphery of the record carrying disk 2, and the brake shoe 23, moves outwardly against the governor friction disk 22, forcing the same outwardly into its 30 normal position, the friction of said brake shoes preventing further operation of the phonograph mechanisms, and provides a means for bringing the record carrying disk 2, to a stop within a very short time, and 35 without noise.

It will of course be understood that any type of motor may be used and that the brake shoes may be otherwise arranged to frictionally contact the operating parts of 40 the phonograph to bring said parts to rest.

I am aware that numerous other details of construction may be varied through a wide range without departing from the principles of this invention, and I therefore do not purpose limiting the patent granted otherwise than necessitated by the prior art. 55

I claim as my invention:

1. The combination with the record playing disk and governor disk of a phonograph, of a pivotally mounted lever, a downwardly 60 projecting arm integrally formed thereon, a brake shoe on the end of said arm disposed adjacent said governor disk, a starting lever connected with said first mentioned lever, means pivotally supporting the starting lever, an angled lever pivotally connected to said starting lever, a brake shoe thereon disposed to the outside of the periphery of said record playing disk, guide means for said angled lever, and slotted means supporting the outer end of said starting lever and permitting a shifting movement thereof to simultaneously actuate said first mentioned lever and said angled lever to move said brake shoes into frictional engagement 65 with said respective governor disk and record playing disk to bring the same to a sudden stop. 70

2. The combination with the rotatable governor disk of a phonograph, of a pivotally mounted angled member, an arm integral therewith, a brake shoe thereon disposed adjacent said governor disk, an apertured actuating lever for receiving the integral end of said angled member, projected 80 therethrough, means pivotally supporting the actuating lever between the ends thereof, said actuating lever adapted when moved into normal position to shift said angled member to move said brake shoe into frictional engagement with said governor disk, 85 to bring the same to a quick stop. 90

In testimony whereof I have hereunto subscribed my name in the presence of two subscribing witnesses.
